Primary Examiner — Susan Bennett Hattan*Assistant Examiner* — Omeed Agilee(74) *Attorney, Agent, or Firm* — Schwegman Lundberg & Woessner, P.A.; Sanjay Agrawal(57) **CLAIM**

The ornamental design for a patient knee cushion set, as shown and described.

DESCRIPTION

FIG. 1 is a perspective view of the right element of a patient knee cushion set incorporating the design.

FIG. 2 is a top view thereof.

FIG. 3 is a bottom view thereof.

FIG. 4 is a right-side view thereof.

FIG. 5 is a left-side view thereof.

FIG. 6 is a front view thereof.

FIG. 7 is a back view thereof.

FIG. 8 is a perspective view of the left element of a patient knee cushion set incorporating the design.

FIG. 9 is a top view thereof.

FIG. 10 is a bottom view thereof.

FIG. 11 is a right-side view thereof.

FIG. 12 is a left-side view thereof.

FIG. 13 is a front view thereof; and,

FIG. 14 is a back view thereof.

The broken lines shown in the drawings illustrate portions of the patient knee cushion set that form no part of the claimed design.

1 Claim, 12 Drawing Sheets(56)
